W. J. BISHOP

AUTOMOBILE DIRECTION INDICATOR

Filed Dec. 6, 1923

UNITED STATES PATENT OFFICE.

WILLIAM JAMES BISHOP, OF COLLINGWOOD, ONTARIO, CANADA.

AUTOMOBILE DIRECTION INDICATOR.

Application filed December 6, 1923. Serial No. 678,969.

To all whom it may concern:

Be it known that I, WILLIAM JAMES BISHOP, a subject of the King of Great Britain, and a resident of the town of Collingwood, in the county of Simcoe, in the Province of Ontario, Canada, have invented certain new and useful Improvements in Automobile Direction Indicators, of which the following is the specification.

10 My invention relates to improvements in automobile direction indicators and the object of the invention is to devise means whereby a plurality of indicating signals positioned one on each side of the vehicle 15 are slidably operable into the operative and inoperative positions, said signals being electrically illuminated when in their operative position, the means for pulling the signals inwardly constituting the means for the 20 transmission of the electric current to the electric illuminating means.

A further object is to devise means whereby each of the signals can be operated independently of the other and in which the 25 electric circuit will be broken when the signal is pulled inwardly.

My invention consists of a direction indicator constructed and arranged all as hereinafter more particularly described and 30 illustrated in the accompanying drawing in which:

Fig. 1 represents a portion of the wind shield and instrument board of a car viewed from the rear side, showing my device applied thereto.

Fig. 2 is a horizontal section through the central portion of my device showing the means for pulling in the respective signals into their inoperative position.

40 Fig. 3 is a rear elevational view of one of my signals showing the means of slidably mounting it.

Fig. 4 is an elevational detail of the right hand double pulley whereby the right hand signal is moved inwardly into the inoperative 45 position.

Fig. 5 is an enlarged section showing the means for giving a rotating movement to the signal carrying hollow spindle.

50 Fig. 6 is an enlarged vertical section through a portion of one of the lower pulleys, such section being taken through the line 6—6 Figure 2.

Fig. 7 is a similar section taken through 55 the line 7—7 Figure 2.

Like characters of reference indicate corresponding parts in the different views.

1 is the dash of the vehicle. 2 is the wind shield. 3 is the rectangular casing adapted to be secured in position in front of the dash 1 and provided with laterally extending hollow arms 4, preferably of tubular form, adapted to receive the hollow signal supporting spindles 5, said signal supporting spindles having the spiral slots 6 therethrough for a portion of their length into which the inwardly turned lugs 7 on the outer ends of the arms 4 project. 8 are the signal casings suitably secured to the outer ends of the spindles 5, as for instance by the socket 9 with the bayonet slot 10 receiving the pin 11, said signal casings being provided with translucent backs and fronts 12 and 13 respectively.

14 are bushings of insulating material inserted into the inner ends of the spindles 5 and adapted to carry the screw plugs 15, each provided with the eye 16. 17 is a wire leading from each screw plug 15 to one terminal of each electric lamp 18, the other terminal of each lamp being grounded.

19 are cables extending inwardly through the arms 4, their outer ends being secured to the eyes 16 on the screw plugs 15. 20 are flanged pulleys journalled in the casing 3 and provided with the superimposed flanged pulleys 21 which are preferably formed integrally therewith and of less diameter than such pulleys 20. These pulleys are constructed of insulating material. The inner ends of the cables 19 are wound about the pulleys 20 and secured thereto as indicated in Figure 4 of the drawing, each pulley 20 being provided with the horizontally disposed contact stud 22 extending to its periphery so as to make contact with the cable 19, each stud 22 being connected to the vertically extending studs 23 which are disposed in the circular grooves 24 cut in the upper faces of the pulleys 20. 25 is a contact plate to which one lead 26 from the battery or other source of electricity is connected, the other terminal of the battery (not shown) being grounded. 27 is a block of insulating material secured in the casing and carrying the contact plate 25 which is provided with outwardly extending opposed hook-shaped lugs 28, the tips of which are adapted to be inserted into the aforesaid grooves 24.

29 are operating cables wound around the drum 21 in the manner shown in Figure 4, their free ends extending freely through the rear face of the casing. 30 are rings 5 on the free ends of the cables adapted to be hooked over suitably disposed pins 31 on the dash.

32 is a spiral spring inserted into each arm 4 and positioned between a plug 33 provided at the inner end of each arm 4 and the insulating bushing 14, said springs normally holding the slideable signal carrying spindles 5 in their outermost position as is illustrated in Figure 3 of the drawing where- 10 in the fronts and backs of the signal casing are disposed vertically.

In operating my device the signals are pulled into their innermost position wherein through the medium of the spiral slots 6 in 20 the spindles 5 the spindles and signal casings are rotated so that the front and back of the signal casings lie horizontally. This is achieved by the driver of the car pulling on the cables 29 through the medium of the 25 rings and if desired to hold the signals in the inoperative position such rings are hooked over the pins 31. Now, should it be desired to indicate that the vehicle is about to turn to the left the left hand ring is re- 30 moved from the pin and through the medium of the spring 32 the left hand spindle 5 will be pushed outwardly, rotating the attached signal casing into the operative position, reeling in the left hand operating cable 35 29 at the same time as the cable 19 is pulled out. The pulling out of the cable 19 rotates the left hand pair of pulleys 20 and 21 the required extent until the contact stud 23 engages the lug 28. When this occurs contact 40 is made between the battery lead 26 and the lamp through the medium of the stud 23, horizontal stud 22 which contacts with the cable 19 which in turn through the plug 15 makes contact with the wiring 17 con- 45 nected to one of the lamp terminals.

When the operating cable 29 is pulled the pulleys 20 and 21 are rotated with the result that the cable 19 is reeled in on the pulley 20 and with it the signal casing spindle, the stud 23 being thus moved out of contact with the lug 28 and breaking the lamp circuit.

Should it be desired to operate the right hand signal the right hand cable 29 is released, permitting the right hand spindle 5 to move outwardly under influence of the spring and thus expose the right hand signal which is constructed in exactly the same manner as the left hand and with the same 55 electrical connection.

Although I have shown pins 31 on the dash, for holding the cables 29 in position so that the signals are in their inoperative

position it will be understood that such cables 29 could be connected to any foot or hand actuating mechanism which is not shown as it forms no part of the present invention.

From the above description it will be seen that I have devised a simple and effective 70 direction indicator for automobiles which when the signals are thrown into their operative position will automatically light the lamps in the signal casings and when such signals are slid into their inoperative position the lamp circuit will be broken.

What I claim as my invention is:

1. In an automobile direction indicator, a signal laterally slideable into and out of the operative position, said signal normally 80 spring-held in its operative position, an electric lamp in the signal, one of its terminals being grounded, a rotatable drum of electrical insulating material, a cable of electrical conducting material secured at one end 85 to the drum and wound thereon, the other end of the cable being connected to the second terminal of the electric lamp, means for rotating the drum, and means coacting therewith adapted to contact with the cable 90 thereon when the signal is in the operative position.

2. In an automobile direction indicator, a signal laterally slideable into and out of the operative position, said signal normally 95 spring-held in its operative position, an electric lamp in the signal, one of its terminals being grounded, a rotatable drum of electrical insulating material, a cable of electrical conducting material secured 100 at one end to the drum and wound thereon, the other end of the cable being connected to the second terminal of the electric lamp, means for rotating the drum, an electrical contact on the drum in engagement with the cable, and a second electric contact adapted to engage the contact on the drum upon the latter being rotated on the signal being slid into the operative position.

3. In an automobile direction indicator, a signal laterally slideable into and out of the operative position, said signal, normally 110 spring-held in its operative position, an electric lamp in the signal, one of its terminals being grounded, a rotatable drum of electrical insulating material, a cable of electrical conducting material secured at one end to the drum and wound thereon, the other end of the cable being connected to the second terminal of the electric lamp, means for rotating the drum, an electrical contact stud on the upper face of the drum in contact with the cable, and a contact finger adapted to engage said stud upon the drum being rotated into the required position.

WILLIAM JAMES BISHOP.
